UNITED STATES PATENT OFFICE

ALICE DE W. LITTLE, OF NEW YORK, N. Y.

DESIGN FOR A MANIKIN HEAD

Application filed November 13, 1929. Serial No. 33,433. Term of patent 7 years.

To all whom it may concern:

Be it known that I, Alice DE W. Little, a citizen of the United States, and a resident of the city, county, and State of New York, have invented a new, original, and ornamental Design for a Manikin Head, of which the following is a specification, reference being had to the accompanying drawings, forming a part thereof.

I claim:—

The ornamental design for a manikin head as shown.

ALICE DE W. LITTLE.
